UNITED STATES PATENT OFFICE.

PHILLIP J. LAMOUREUX, OF MARINETTE, WISCONSIN.

SLICE FOR PAPER-MAKING MACHINES.

Application filed September 1, 1927. Serial No. 216,958.

This invention relates to a slice to be used in paper making, and is designed primarily to be used in connection with paper making machines of the Fourdrinier type, but it is to be understood that a slice, in accordance with this invention, may be employed in connection with any type of machine or for any purpose for which it is found applicable, and the invention has for its object to provide, in a manner as hereinafter set forth, a slice of the class referred to for increasing the output of the machine without increasing the cost of maintenance by constructing and arranging the slice in a manner to form a smooth unobstructed passage for the pulp around the rear of the slice, whereby the pulp will travel under the slice with almost absolute freedom from lumps or voids, thereby overcoming the formation of eddies and the gathering of the pulp at such point resulting in retardation of the operation of the machine due to the time lost in freeing the pulp for passage to the making wire.

A further object of the invention, is to provide, in a manner as hereinafter set forth, a one-piece, resilient, adjustable slice for regulating the flow of paper pulp or stock onto the making wire of the machine.

A further object of the invention is to provide, in a manner as hereinafter set forth, a slice for use in connection with paper making for producing a product of uniform thickness and with lumps and apertures in the product reduced to a minimum.

Further objects of the invention are to provide, in a manner as hereinafter set forth, a slice of the class referred to, which is simple in its construction and arrangement, strong, durable, compact, thoroughly efficient in its use, readily installed, conveniently adjusted and set in adjusted position, and comparatively inexpensive to manufacture.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations, and modifications can be resorted to which will fall

within the scope of the claims hereunto appended.

In the drawings wherein like reference characters denote corresponding parts throughout the several views:—

Figure 1 is a fragmentary view, broken away, in side elevation of a paper making machine showing the adaptation therewith of an adjustable slice in accordance with this invention.

Figure 2 is a fragmentary view, in vertical section of a paper making machine, showing the adaptation therewith of an adjustable slice in accordance with this invention and with the slice in vertical section.

Figure 3 is a front elevation, partly in section, of a slice in accordance with this invention, and showing the adaptation thereof in connection with a paper making machine.

Figure 4 is a section on line 4—4, Figure 3.

Referring to the drawings in detail, there is illustrated a breast roll 1, making wire 2, a box or container 3, for the body of pulp or stock 4. The side walls, bottom and the front wall 7 of the box 3, are indicated respectively at 5, 6 and 7. The foregoing elements are a part of a paper making machine of the Fourdrinier type and illustrated by way of example to show the adaptation of a slice, in accordance with this invention, therewith.

The front wall 7 of the box 3, is inset with respect to the forward ends of the side walls 5 of said box. The bottom 6 has its lower face, at its forward end, bevelled as at 8, and positioned over the making wire 2, at the high part of the latter when travelling around the breast roll 1. The breast roll 1 operates in a counter-clockwise direction and provides for the upper portion of the making wire 2 to travel forwardly with respect to the forward end of the bottom 6. The pulp or stock 4 is discharged from the box 3 over the forward end of the bottom 6 and upon the making wire 2. As is well known, the upper face of the bottom 6, at the forward end thereof, is provided with the ordinary apron board, and the latter is not shown.

The slice, in accordance with this invention, controls the discharge of the pulp or

stock 4 from the box 3 onto the making wire 2. The slice comprises a slice member formed of one piece of material, preferably sheet metal and possessing a resilient characteristic of the desired degree. The major part of the slice member is disposed at an obtuse angle with respect to the bottom 6 and said major part projects forwardly from the front wall 7 of the box 3 towards the bottom 6 and at a downward inclination. The slice member will be referred to more specifically hereinafter.

The front wall 7 of the box 3 has its bottom edge positioned a substantial distance above the bottom 6 and owing to the position of said wall 7, with respect to the bottom 6, an outlet for the pulp or stock 4, is provided, and said outlet is controlled by the slice member. The front wall 7 has its bottom edge positioned a substantial distance rearwardly with respect to the forward edge of the bottom 6. The forward edge of the bottom 6 is positioned slightly rearwardly with respect to the forward edges of the side walls 5 of the box 3. Each side wall 5 of the box 3 is formed with a rectangular opening 9 having the major portion thereof projecting forwardly with respect to the wall 7. The opening 9 extends rearwardly a small distance with respect to the front wall 7 of the box 3.

A slice, in accordance with this invention and for the purpose referred to, comprises a vertically adjustable supporting plate 10 which is positioned against the forward face of the front wall 7 and extends from one side wall 5 to the other side wall 5 of said box 3. The plate 10 is of rectangular contour and its width thereof is materially less than the height of the front wall 7. The plate 10 extends from the lower part of the opening 9 to the lower end of the front wall 7. The lower face of the front wall 7 is bevelled as at 11 and the lower edge of the plate 10 is bevelled as at 12. The bevel of the lower edge 12 of the plate 10 is at the same angle as the bevel of the lower edge of the wall 7, but the edge 12 of the plate 10 is arranged slightly above the lower end of the wall 7. The plate 10 has the marginal portion of its inner face, at its bottom thereof, mortised, as at 13, and which provides a shoulder 14. The mortise 13 extends from one end to the other end of the plate 10. The mortise 13, not only provides a shoulder 14, but in connection with the lower part of the forward face of the wall 7 forms a socket or pocket 15. Each end of the plate 10 is provided with a forwardly extending right angularly disposed flange 16. The flanges 16 abut against the inner faces of the side walls 5 of the box 3. The plate 10 is slidably connected against the forward face of the front wall 7 of the box 3, by a pair of vertically disposed combined guide and retaining mem-

ber 17 which overlap the flanges 16, abut against the side walls 5, are fixedly secured to these latter by the holdfast devices 18, and extend to the forward face of the wall 7. The adjusting means for the plate 10 will be presently referred to.

The plate 10 at its top is formed with a forwardly directed, right angularly disposed ledge or support 19 of suitable width and which extends from one end to the other end of the plate. The ledge 19 is provided with a series of spaced openings 20. Projecting laterally from the rear of each end of the ledge 19, is an arm 21, of appropriate length, and which is formed with a vertically disposed opening 22 having a threaded wall. The arms 21 project in opposite directions with respect to each other and extend through the openings 9. The arms 21 project a substantial distance from the side walls 5 of the box 3. Secured to the outer faces of the side walls 5, and arranged below each arm 21, is an angle shaped bracket 23, provided with a socket 24 and a retaining screw 25, and the latter is mounted in a manner to project towards the walls 5 and to extend into the socket 24. Extending through the arms 21, and threadedly engaging with the walls of the openings 22, are adjusting elements 26 for vertically shifting the plate 10. Each adjusting element or member consists of a peripherally threaded cylindrical shank 27, provided at its top with a head 28, formed with a knurled edge. The lower end of the shank 27 is reduced, as at 29, and is not formed with threads, but is provided with an annular groove 30 into which projects the inner end of the screw 25, whereby the shank 27 will be rotatably connected to a bracket 23. Mounted on the shank 27 and positioned above the arm 21, is a binding nut 31, having a knurled edge.

The slice member is indicated generally at 32, and in cross section, formed of a major part 33 and a part 34 which is disposed vertically with respect to the major part 33. The parts 33, and 34 are disposed at an angle with respect to each other, and the cross sectional width of the major part 33 is materially greater than the cross sectional width of the part 34. In cross section the major part 33 extends in the same plane throughout and the plane of the major part 33 is at an obtuse angle with respect to the bottom 6 of the box 3. The inclination of the major part 33 conforms to the inclination of the bevelled lower edge of the plate 10. The lower face of the major part 33 at its rear aligns with the bevelled lower end 11 of the front wall 7 of the box 3. The part 34 of the slice member is positioned within the mortise 13, or rather in the socket or pocket 15 formed by the mortise 13 and front wall 7 of the box 3. The part 34 abuts against the shoulder 14 and is secured

against the rear face of the plate 10, by the holdfast devices 35. The bottom edge of the plate 10 abuts against the upper face of the major part 33, at the rear thereof.

5 Fixedly secured to the upper face of the major part 33, of the slice member 32, in proximity to the forward edge of said part 33, are spaced, upstanding yoke-shaped brackets 36, and into each of said brackets 10 extends the lower end 37, of an adjusting rod 38 and with the latter disposed at a rearward inclination from its lower to its upper end. The lower ends 37 of the adjusting rods 38 are pivotally connected to the 15 brackets 36, by the pivots 39. The upper portion of each of the rods 38 is peripherally threaded as at 40. Each rod extends upwardly through an opening 20 in the ridge 19. Carried by each rod 38 is an upper and 20 a lower combined adjusting and binding nut 41, 42 respectively, the former being arranged above the ridge 19 and the latter below said ridge. The nut 41 at its upper end is formed with an annular flange 43, and the 25 nut 42 at its lower end with an annular flange 44. The flanges have their edges knurled and provide means for conveniently turning the nuts on the rods, for the purpose of vertically adjusting the rods.

30 The slice member 32 extends from one end wall 5 to the other end wall 5 of the box 3 and the angle of the part 33 of said member, relative to the upper face of the bottom 6, can be varied by adjusting the rods 38.

35 The slice member can be adjusted, relative to the bottom 6, at various points, throughout its length, due to the fact that the adjusting rods 38 are disposed in spaced relation throughout said slice member and can 40 be vertically adjusted. The openings 20 are of a diameter whereby the rods 38, when adjusted, can be shifted to varying rearward inclinations, when desired. The plate 10, adjusting rods 38 and the slice member 32 45 can be bodily adjusted vertically by the adjusting members 27, engaging with the threaded walls of the openings in the arms 21. The adjusting members 27 maintain the ridge stationary and in set position. The 50 guide members 17 slidably connect the plate 10, against the forward face of the front wall 7 of the box 3. The openings 20, and the ridge 19, are arranged rearwardly with respect to the yoke-shaped brackets 36.

55 The construction and arrangement of the slice member 32, forms a smooth unobstructed passage for the pulp or stock and overcomes the forming of eddies and the gathering of the pulp as it travels in the 55 direction of discharge towards and onto the making wire 2. The angular dispositions throughout of the major portion 33 of the slice 60 32, with respect to the bottom 6, provides an unobstructed passage and permits the stock to go under the slice with almost

absolute freedom from lumps or voids, and under such conditions the gathering of the pulp at such point is prevented. When the pulp is obstructed, eddies are formed and the pulp gathers and has to be freed by 70 manual means, and this results in the retardation of operation of the machine. The objections pointed out are overcome by the construction and arrangement of the slice as aforesaid, and therefore the slice provides for an increase in output with respect to the machine, without an increase in the cost of maintenance, therefore it is thought that the many advantages of an adjustable, 80 flexible slice, in accordance with this invention and for the purpose set forth, can be readily understood, and although the preferred embodiment of the invention is as illustrated and described, yet it is to be understood that changes in the details of construction can be had which will fall within the 85 scope of the invention as claimed.

What I claim is:—

1. In a slice for paper making, a vertical disposed, slidably connected plate, a slice 90 member connected to the lower portion of said plate and having its major part projecting forwardly from said plate at a downward inclination, upstanding, angularly adjusting means for and pivotally connected to 95 said major part of said member and slidably connected with said plate, said adjusting means carrying elements coating with the plate for maintaining the adjusting means in set position, and means connected with 100 said plate for vertically adjusting it and for maintaining it in adjusted position.

2. In a slice for paper making, a vertically disposed, slidably connected plate provided at its top with a forwardly directed ridge, a 105 slice member having the major portion thereof disposed at a downward inclination and its other portion fixedly secured to the lower end of said plate, inclined adjusting bars for the inclined portion of said member, said bars pivotally connected at their lower ends to said inclined portion and having their upper ends extending through said ridge, means carried by said bars for vertically adjusting them, said means coating with said 110 ridge for maintaining said bars in adjusted position, and means for vertically adjusting said plate and for maintaining it in adjusted 115 position.

3. In paper making machines of that type 120 including a pulp box having its bottom and top arranged to provide an opening or outlet at the lower portion of the front thereof for the discharge of the pulp, the combination of a unitary slice member positioned over said bottom for controlling said outlet, said member including a vertically disposed part and a part extending forwardly from the latter and at an obtuse angle with respect to said bottom, said obtuse angled part, in 125 130

transverse cross section, extending in the same plane throughout, vertically adjustable supporting means connected against the front of said vertical part, and angularly adjustable elements for and pivotally connected to said obtuse angled part and slidably connected to said means forwardly from the latter, said means and elements having co-acting means for retaining said elements in adjusted position. In testimony whereof, I affix my signature hereto. 10

PHILLIP J. LAMOUREUX.
